REVERSING-GEARING FOR WRINGERS.

1,224,962.

Specification of Letters Patent.

Patented May 8, 1917.

Application filed April 20, 1915. Serial No. 22,547.

To all whom it may concern:

Be it known that I, FREDERICK W. SAUER, a citizen of the United States, residing at Hollis Court, county of Queens, and State 5 of New York, have invented new and useful Improvements in Reversing-Gearing for Wringers, of which the following is a specification.

This invention is an improvement in driving mechanism for power-driven clothes wringers, the object being to provide a simple, safe and efficient construction. The invention comprises certain features of construction and combinations of parts, which 15 will be hereinafter described and more particularly pointed out in the appended claims.

In the accompanying drawings illustrating the invention:

Figure 1 is a side elevation of the wringer; 20 Fig. 2 is an end elevation thereof;

Fig. 3 is an elevation looking at the opposite end;

Fig. 4 is an enlarged fragmentary sectional end elevation, showing the gearing; 25

Fig. 5 is a vertical section, taken at right angles through Fig. 4;

Fig. 6 is a detail enlarged section on the line 6—6 of Fig. 4; and

Fig. 7 is an enlarged perspective view of 30 plate 29.

The wringer frame 1 may be in general of ordinary construction, and has end pieces 2 formed with the usual vertical slots 3 receiving the bearings 4 and 5 of the upper 35 and lower rollers 6 and 7, springs 8 being disposed within the slots to press down upon the bearings of the upper roller.

On one end of the frame, opposite the end of the lower roller, is a box 9, which 40 may be fixed in place by inward projecting wings 10 screwed to opposite sides of the frame, as indicated. The journal end 11 of the lower roller is extended into this box and bears a bevel gear 12. A transverse 45 drive shaft 13 is journaled in the box, opposite and at right angles to the journal of the lower roller, and bears opposed loose bevel pinions 14, which mesh simultaneously with the gear 12 at opposite sides of the 50 center of the latter. The ends of the shaft 13 extend through bearings 15 in the side walls of the box 9, and are formed at their projecting portions 16 so that either of them may receive a driving connection. A 55 double clutch member 17 is splined to slide

on the shaft 13 between the pinions 14, which are provided on their inner ends with clutch formations, so that they may be coupled alternately to the drive shaft, the distance between the pinions being sufficient, 30 so that when the clutch member 17 is in mid-position, neither of the pinions is driven, and the wringer is consequently at rest, even though the shaft 13 continues to revolve. 65

The clutch member may be shifted by a lever 18, which is fulcrumed intermediate its ends at 19 to a plate 20 fixed to the end piece of the wringer frame below the box 9. The upper end of this lever is formed with a fork 21 engaging a central groove in the clutch member 17 and the lower end of the lever is rounded, as shown at 22, for engagement by a forked rocker 23 on one end of a rock-shaft 24. The said rock-shaft 75 extends across the lower portion of the frame, through both end pieces thereof, and at its opposite end bears a handle 25. The said handle is adapted to engage with a retainer 26 on the face of the end piece 2, 70 opposite the end piece which bears the box 9. The retainer 26 is formed with a central notch to hold the handle in the position which places the clutch member 17 between 80 and out of engagement with both of the 85 pinions 14. By withdrawing the handle from this notch and rocking it past one end of the retainer or the other, the clutch member is shifted in the corresponding direction to couple the selected pinion 14 with 90 the drive shaft, thus causing the wringer to operate in either direction which may be desired. The rock-shaft is longitudinally movable to permit the withdrawal of the handle 25 from engagement with the retainer, and is constantly urged lengthwise 95 in the direction to hold it to such engagement by means of a compression spring 27 interposed between the rocker 23 and the plate 20. The rocker, it will be observed 100 from Fig. 1, is of sufficient width to remain in engagement with the lower end of the lever 18, irrespective of the longitudinal movement of the rock-shaft. A tube 28 is preferably provided, extending between the 105 end pieces of the frame, for inclosing the rock-shaft.

In order to insure proper engagement between the pinions 14 and the gear 12, means are provided for preventing upward move- 110

ment of the end of the lower roller which is engaged by the drive mechanism. In the particular embodiment illustrated, a plate 29 is carried by the journal end 11 of the 5 roller, being formed with an opening 30 for the reception of this shaft. The plate is provided with portions, preferably in the 10 form of pins 31, engaging the sides of the slot 3 in such manner as to keep the plate from turning. A screw 32 is threaded downward through an overhanging portion 33 of the box 9 to bear against the top of the plate 29, which may be provided with an 15 extension 34, as shown in Fig. 7. This screw constitutes an adjustable abutment, preventing upward movement of the plate 29, and therefore of the end of the lower roller.

What is claimed as new is:

1. In driving mechanism for wringers, 20 the combination with a vertical frame, and a driven member journaled therein, of a box fixed to one end of the frame adjacent the end of the driven member, a bevel gear on the said end of the driven member within 25 said box, a transverse driving shaft journaled in said box, opposed bevel pinions loose on said shaft within the box meshing with the bevel gear, a double clutch member splined on the shaft between the pinions 30 and adapted to engage alternately therewith, a lever fulcrumed intermediate its ends on the end of the frame and engaging at its upper end with said clutch member, and a 35 rock-shaft extending across the lower portion of the frame through the end pieces thereof, one end of said shaft bearing a rocker engaging the lower end of said lever and the remote end of the shaft bearing a handle outside the opposite end of the frame.

40 2. In driving mechanism for wringers, the combination with a vertical frame, and a driven member journaled therein, of a box fixed to one end of the frame adjacent the end of the driven member, a bevel gear on 45 the said end of the driven member within said box, a transverse driving shaft journaled in said box, opposed bevel pinions loose on said shaft within the box meshing with the bevel gear, a double clutch member splined on the shaft between the pinions 50 and adapted to engage alternately therewith, a lever fulcrumed intermediate its ends on the end of the frame and engaging at its upper end with said clutch member, a 55 rock-shaft extending across the lower portion of the frame through the end pieces thereof, one end of said shaft bearing a rocker engaging the lower end of said lever and the remote end of the shaft bearing a 60 handle outside the opposite end of the frame,

a retainer on this end of the frame for engagement by the handle, the rock-shaft being longitudinally movable to release the handle from the retainer, and a spring urging the rock-shaft lengthwise to hold the 65 handle in engagement with the retainer.

3. In driving mechanism for wringers, the combination of a vertically slotted frame, a driven member journaled in bearings in the 70 slots of said frame, a box fixed on one end of the frame opposite the end of the driven member, a gear on the end of said driven member, driving means mounted in said box for driving the driven member in either direction, and an abutment preventing the adjacent end of the driven member from rising. 75

4. In driving mechanism for wringers, the combination of a vertically slotted frame, a driven member journaled in bearings in the 80 slots of said frame, a box fixed on one end of the frame opposite the end of the driven member, a gear on the end of said driven member, driving means mounted in said box for driving the driven member in either 85 direction, and an adjustable abutment on said box for preventing upward movement of the adjacent end of the driven member.

5. In driving mechanism for wringers, the combination of a vertically slotted frame, a driven member journaled in bearings in the 90 slots of said frame, a box fixed on one end of the frame opposite the end of the driven member, gearing in the box for driving the driven member in either direction, a plate on the adjacent end of the driven member, 95 said plate being held against rotation, and an abutment screw extending downward through an overhanging portion of said box to bear against said plate.

6. In driving mechanism for wringers, the 100 combination of a frame having vertically slotted end pieces, a driven member journaled in bearings in the slots of said end pieces, a box fixed on one end of the frame opposite the end of the driven member, gearing in the box for driving the driven member in either direction, a plate on the 105 adjacent end of the driven member, said plate having portions engaging the sides of the slot in the frame end piece to keep the 110 plate from turning, and an abutment on the box coöperative with said plate to prevent upward movement thereof and of the end of the driven member.

Dated April 15th, 1915.

FREDERICK W. SAUER.
